Nelson W. Boardman

UNITED STATES PATENT OFFICE

THOMAS LUND, OF BEVERLY, MASSACHUSETTS, ASSIGNOR TO UNITED SHOE MACHINERY CORPORATION, OF PATERSON, NEW JERSEY, A CORPORATION OF NEW JERSEY

HEEL-ATTACHING MACHINE

Application filed March 20, 1929. Serial No. 348,568.

This invention is directed to heel-attaching machines, relating particularly to that part of the apparatus which holds and presents to the heel-seat of a jacked shoe a heel or heel-portions, as a base and top-lift, which are to be nailed in place.

Sometimes heels are very large, and it becomes impossible to position side by side both a base and a top-lift within the area available upon the ordinary swing-plate actuated by a connection to the loader-arm which supplies nails to the die-block. This is due to the fact that the sectors in which the heel-portions are received, narrow rapidly as they approach the axis of oscillation of the swing-plate. To overcome this difficulty, it has been customary to place the heel-base and top-lift by hand upon the die-block for attachment, this materially increasing the time required. To hold the maximum sizes of heels in a swing-plate has called for a redesign of the machine-frame.

It is an object of this invention to so organize the heel-holding mechanism of a heel-attaching machine that there may be ample room to carry together a base and a top-lift of the largest size, while still employing the effective actuation of the holder from the loading mechanism. To attain this result, I combine with the nailing mechanism and oscillatory loader of a heel-attaching machine, a reciprocating base- and top-lift-holder, which is mounted to slide in co-operation with the nailing mechanism, and is connected to the loader to transform the oscillation of said loader into rectilinear movement at the holder through a lever fulcrumed at a relatively fixed point as compared with the reciprocating travel of the holder. The lever engages the holder to move it in one direction, while a spring exerts its force to carry the holder in the opposite direction. Against the action of the spring, the holder is latched for release at the desired time. With such a sliding plate, or one hav-

ing rectilinear movement, as distinguished from the oscillation of the swing-plate, the largest heel-portions may be carried without changes in the dimensions of the associated elements of the heel-ing machine, since with 50 it the longitudinal axes of the portions, or those perpendicular to the centers of the breasts, are parallel to each other, instead of converging rearwardly. The heel-portions therefore do not encounter, at the rear, contracted spaces which would demand a considerable increase in the dimensions of the plate to give proper clearance. Actuated from the loading mechanism, in combination with a spring, the operation of my improved mechanism is simple and direct. The latch which retains the holding plate against the force of the spring preferably engages the plate itself, and is shown as releasable to allow the spring to act, as by means movable 55 with the drivers of the nailing mechanism. After this, the latch is freed from the releasing means, which may continue its travel to normal. Because, to alter the pressure upon the work, it is a common practice to adjust the die-block-holder upon which the heel-holding plate with its retaining latch is mounted, in the present instance I may provide novel means arranged to vary the 60 normal relation between the latch and its releasing means, thus compensating for the changes produced by the pressure-adjustment. In the specific embodiment of the invention herein disclosed, the latch for the plate and the cross-head bearing the drivers 65 may carry hooks, which engage and cause the release of the plate from the latch during the travel of the cross-head. A projection from the frame may contact with a cam-surface upon the releasing hook, and move 70 this laterally to disengage it from the latch-hook.

In the accompanying drawings, a single illustrative embodiment of the invention appears,

Fig. 1 being a broken horizontal section of a portion of a heeling machine, this view being taken in a plane just above the die-block; and

Fig. 2, a perspective view of one end of the holding plate taken from the rear of the machine and particularly showing the latching and releasing means.

I have chosen to illustrate the invention in connection with that type of heeling machine made the subject of United States Letters Patent No. 1,157,688, Glidden, October 26, 1915. A portion of the machine-frame is indicated at 10, in this frame there being mounted for vertical reciprocation a holder 12 furnishing a support for a die-block 14, and a cross-head 16 bearing drivers 18 extending into openings in the die-block. Movement is imparted, respectively, to the die-block-holder, to apply final pressure to the work, and to the cross-head, to cause the drivers to insert the nails resting upon their upper ends, through rods 20, 20 and surrounding sleeves 22, 22 reciprocated by the power mechanism of the machine. The jack which carries the shoe to be heeled above the die-block is not illustrated. To deliver the attaching nails to the die-block-openings, loading mechanism is associated with the nailing mechanism, it being shown as having an arm 24 supporting a loader-block 26, this block being provided with nail-carrying openings 28 corresponding to those of the die-block. The arm is arranged to oscillate in a horizontal plane about a vertical rod 30 fixed in the machine-frame above the die-block, from a nail-receiving position, as appears in Fig. 1, to a nail-delivering position, against a stop-screw 27 threaded through a projection from the frame, in which last-mentioned position the openings 28 register with those of the die-block.

To hold and present to the nailing mechanism such heel-portions as bases and top-lifts of leather, rubber or other material, a substantially horizontal plate 32 is mounted to reciprocate above the die-block. At its rear portion it is guided by a rod 34, shown as extending horizontally through a groove in the die-block-holder. Its forward portion may slide upon the upper surface of the die-block. Arranged side by side, in parallel relation, upon the upper face of the plate is a heel-base-holding device H and a top-lift-holding device T. Each device may include an adjustable rear fork 36 and a yieldable breast-bar 38, these respectively clamping upon the plate a base h and a top-lift t. A helical spring 40 connects the plate with a bracket 42 projecting from the rear and to one side of the die-block-holder 12. This spring serves to draw the plate into its top-lift-presenting position, the movement being limited by an adjustable stop-screw 44 threaded through a portion of the bracket.

The rate of travel of the plate under the influence of the spring may be reduced by a dash-pot device 45. To the base-presenting position, the plate is forced by a lever 46 fulcrumed upon the bracket 42 and provided with a rounded end arranged to contact with a turned-up lug 48 upon the plate when the nailing mechanism is inactive and the die-block-holder is in its normal position. Pivoted at its opposite ends to the lever and to the loader-arm 24 is a link 50. The lever is thus compelled to oscillate with the loader-arm, but in the opposite direction. That is, as the arm swings to the left (Fig. 1) to its nail-delivering position over the die-block, the rounded end of the lever moves to the right toward the die-block and then reversely. Thus, as an incident to the delivery of nails to the die-block, the plate 32 is compelled to assume its base-presenting position, and allowed to be shifted by the spring 40 to its top-lift-presenting position.

In its heel-presenting relation, the plate is temporarily maintained against the tension of the spring 40 by a latch 52 in the form of a bell-crank lever fulcrumed at the inner extremity of the bracket 42 and having a vertical arm arranged for engagement with a contact-block 54 at the under side and rear of the plate 32. To enable the base to be correctly located by the plate upon which it is clamped by the device H, the block is adjustably secured by slot-and-screw connections 56. The latch is maintained in normal retaining engagement with the block by a spring 58, which draws it against a stop-screw 60. To allow the spring 40 to carry the plate 32 to its top-lift-presenting position, the latch is drawn away from the block 54 by means movable with the drivers 18 as these descend after nailing the base. Depending from a horizontal arm of the latch-lever is a hook 62 supported for vertical adjustment by nuts 64 upon a threaded shank 66. From the rear of the cross-head 16 projects an arm 68, upon which is pivoted a releasing or actuating hook 70 with its engaging end movable into contact with and above the corresponding end of the hook 62. This hook 70 is allowed to yield against a spring 72, so it may assume the relation just indicated. Upon descent of the cross-head, the now overlapping ends of the hooks cause the retaining end of the latch 52 to be moved horizontally away from the block 54, thus releasing the holder-plate. When this has been accomplished, a cam-surface 74 upon the hook 70 strikes a contact-projection 76 at the end of a bracket 78 secured to the frame 10. The hook 70 is thereby swung away from the hook 62, so the latch 52 is freed and returned by its spring 58 for the retention of the plate 32.

At the beginning of a heel-attaching operation, the holder-plate 32 will be at the left extreme of its travel, as viewed in Fig. 1 of

the drawings, against the stop-screw 44. Nails having been supplied to the openings 28 of the loader-block 26, as by a distributing mechanism or manually, the operator turns the loader-arm 24 in a clockwise direction until, when it is in contact with the stop-screw 27, its openings are alined with those in the die-block 14. The nails are thereupon released by the tripping of their supporting shutter, 5 and fall into the die-block-openings, resting heads-down upon the ends of the drivers 18. During this movement of the loading mechanism, the connections between it and the lever 46 acted to force the rounded end of said lever 10 against the contact-lug 48 of the holder-plate, carrying this to its opposite extreme position. In this travel, the block 54 strikes an inclined end of the latch 52, moving it aside. The spring 58 returns the latch after the 15 block has passed it, and the plate is now retained with its clamping device H in base-presenting relation over the die-block. At this time, the operator supplies the holder with a base h and a top-lift t inserted, respectively, in the clamping devices H and T, and depresses the starting treadle of the machine. Pressure having been applied to the work in the usual manner by the downward travel of the jack and upward travel of the die-block, 20 the cross-head rises, forcing the nails through the base and into the heel-seat of the shoe, where they are clinched. During this elevation of the cross-head, the hook 70, rising with it, yields against its spring 72, so that it may 25 pass the end of the hook 62 and engage this. The succeeding descent of the cross-head with the hook 70 draws down the hook 62 and swings the engaging end of the latch away from the block 54. The plate 32 is thereby 30 released, and the spring 40 restores it to its initial position against the stop-screw 44. This having been accomplished, the cam-surface 74 of the hook 70 strikes the contact-projection 76, separating the hooks and thus 35 freeing the latch 52 for return by its spring 58 to its normal plate-retaining position. Now the top-lift t is above the die-block, alined with the attached base, and a second treadling of the machine causes this 40 to be attached. The movement of the hook 70 in this case is an idle one. Upon the removal of the work from the jack, the apparatus is ready for the heeling of another shoe. It is particularly to be noted that, 45 because of the parallel relation between the base and top-lift held upon the plate 32, ample space is furnished at the rear of the plate to receive these portions for heels of large size, and that the control of the plate is through a 50 simple and direct connection to the usual loading mechanism, this connection being of such a character that the oscillation of the loading mechanism produces reciprocation of the plate.

Having described my invention, what I

claim as new and desire to secure by Letters Patent of the United States is:

1. In a heel-attaching machine, nailing mechanism, an oscillatory nail-loader delivering thereto, a reciprocatory heel- and top-lift-holder mounted to slide in co-operation with the nailing mechanism, a lever fulcrumed at a point fixed relatively to the holder and arranged to contact therewith, and connections to the loader for actuating the lever. 70

2. In a heel-attaching machine, nailing mechanism, an oscillatory nail-loader delivering thereto, a reciprocatory heel- and top-lift-holder mounted to slide in co-operation with the nailing mechanism, a lever fulcrumed at a point fixed relatively to the holder and arranged to contact therewith, a spring exerting its force to move the holder toward the lever, and connections to the 80 loader for actuating the lever.

3. In a heel-attaching machine, nailing mechanism, an oscillatory nail-loader delivering thereto, a reciprocatory heel- and top-lift-holder mounted to slide in co-operation with the nailing mechanism, a lever fulcrumed at a point fixed relatively to the holder and arranged to contact therewith, a spring exerting its force to move the holder toward the lever, connections to the loader 85 for actuating the lever, and a latch for retaining the holder against the force of the spring. 95

4. In a heel-attaching machine, nailing mechanism including a die-block and its holder, a guide extending along the die-block-holder, a holder-plate mounted to slide upon the guide, a loader-arm pivoted to oscillate over the die-block-holder, and connections pivoted to the loader-arm and movable into contact with the plate for sliding said plate. 100

5. In a heel-attaching machine, nailing mechanism including a die-block and its holder, a guide extending along the die-block-holder, a holder-plate mounted to slide upon the guide, a loader-arm pivoted to oscillate over the die-block-holder, a lever fulcrumed upon the die-block-holder for contact with the plate, and a link pivoted to the lever and loader-arm. 110

6. In a heel-attaching machine, nailing mechanism including a die-block and its holder, a guide extending along the die-block-holder, a holder-plate mounted to slide upon the guide, a loader-arm pivoted to oscillate over the die-block-holder, a lever fulcrumed upon the die-block-holder for contact with the plate, connections between the lever and loader-arm, and a spring extending between the die-block-holder and plate and arranged to draw the plate into contact with the lever. 115

7. In a heel-attaching machine, nailing mechanism including a die-block and its holder, a guide extending along the die-block-holder, a holder-plate mounted to slide upon the guide, a loader-arm pivoted to oscillate 120

125

over the die-block-holder, a lever fulcrumed upon the die-block-holder for contact with the plate, connections between the lever and loader-arm, a spring extending between the die-block-holder and plate and arranged to draw the plate into contact with the lever, and a latch carried by the die-block-holder and co-operating with the plate.

8. The combination with nailing mechanism having reciprocatory drivers, of a movable heel-holder co-operating with the nailing mechanism, a latch for the holder, and means movable with the drivers for releasing the latch during the idle movement of said drivers.

9. The combination with nailing mechanism having reciprocatory drivers, of a movable heel-holder co-operating with the nailing mechanism, a latch for the holder, means movable with the drivers for releasing the latch during the idle movement of said drivers, and means arranged to vary the normal relation between the latch and releasing means.

10. The combination with nailing mechanism having reciprocatory drivers, of a movable heel-holder co-operating with the nailing mechanism, a latch for the holder, means movable with the drivers for releasing the latch, and means for freeing the latch from the releasing means.

11. The combination with nailing mechanism having reciprocatory drivers, of a movable heel-holder co-operating with the nailing mechanism, a latch for the holder, means movable with the drivers for releasing the latch, and means fixed in position relatively to the drivers for freeing the latch from the releasing means.

12. The combination with nailing mechanism, of a reciprocatory heel-base- and top-lift-holder, means arranged to move the holder into position to present a base to the nailing mechanism, a spring exerting its force to move the holder into top-lift-presenting position, a latch for temporarily retaining the holder in its base-presenting position, a hook carried by the latch, and a traveling releasing hook arranged to engage the latch-hook.

13. The combination with nailing mechanism, of a reciprocatory heel-base- and top-lift-holder, means arranged to move the holder into position to present a base to the nailing mechanism, a spring exerting its force to move the holder into top-lift presenting position, a latch for temporarily retaining the holder in its base-presenting position, a hook carried by the latch, a traveling releasing hook arranged to engage the latch-hook, and means arranged to adjust one of the hooks toward and from the companion hook.

14. The combination with nailing mechanism, of a reciprocatory heel-base- and top-lift-holder, means arranged to move the holder into position to present a base to the

nailing mechanism, a spring exerting its force to move the holder into top-lift-presenting position, a latch for temporarily retaining the holder in its base-presenting position, a hook carried by the latch, a reciprocatory hook arranged for engagement with the latch-hook during movement in one direction, and means for moving the reciprocatory hook out of engagement with the latch-hook during movement in the opposite direction.

15. The combination with nailing mechanism, of a reciprocatory heel-base- and top-lift-holder, means arranged to move the holder into position to present a base to the nailing mechanism, a spring exerting its force to move the holder into top-lift-presenting position, a latch for temporarily retaining the holder in its base-presenting position, a hook carried by the latch, a reciprocatory hook arranged for engagement with the latch-hook during movement in one direction, and a contact member arranged to move the reciprocatory hook during its travel in the opposite direction laterally out of engagement with the latch-hook.

16. In a heel-attaching machine, a frame, a die-block and its holder supported by the frame, a cross-head reciprocating upon the frame and carrying drivers co-operating with the die-block, a heel-base- and top-lift-holding plate mounted to reciprocate upon the die-block-holder, a spring connecting the plate and holder, a latch pivoted upon the holder for engagement with the plate, a member movable upon the cross-head and operating the latch, said member being provided with a cam-surface, and a projection from the frame arranged for contact with the cam-surface.

17. In a heel-attaching machine, a frame, a die-block and its holder supported by the frame, a cross-head reciprocating upon the frame and carrying drivers co-operating with the die-block, a heel-base- and top-lift-holding plate mounted to reciprocate upon the die-block-holder, a spring connecting the plate and holder, a latch pivoted upon the holder for engagement with the plate, a member variable in position upon the latch, and a member carried by the cross-head for engagement with the latch member.

18. In a heel-attaching machine, a frame, a die-block and its holder supported by the frame, a cross-head reciprocating upon the frame and carrying drivers co-operating with the die-block, a heel-base- and top-lift-holding plate mounted to reciprocate upon the die-block-holder, a spring connecting the plate and holder, a latch pivoted upon the holder for engagement with the plate, and co-operating hooks carried by the latch and cross-head and arranged to release the latch.

19. In a heel-attaching machine, a frame, a die-block and its holder supported by the

frame, a cross-head reciprocating upon the frame and carrying drivers co-operating with the die-block, a heel-base- and top-lift-holding plate mounted to reciprocate upon the die-block-holder, a spring connecting the plate and holder, a latch pivoted upon the holder for engagement with the plate, co-operating hooks carried by the latch and cross-head and arranged to release the latch, the hook upon the cross-head being pivoted, and a member fixed upon the frame and contacting with the cross-head-hook to effect its movement.

In testimony whereof I have signed my name to this specification.
